VENDING MACHINE

Albert E. Gebert, Wilmette, and Floyd C. Black,
Chicago, Ill., assignors to Advance Machine
Co., Chicago, Ill., a corporation of Illinois

Application October 30, 1935, Serial No. 47,436

20 Claims. (Cl. 194—2)

This invention relates to improvements in vending machines, and one of the objects of the same is to provide an improved machine of this character from which a plurality of commodities may be vended, each of the commodities supply being provided with its individual ejecting or vending mechanism, the ejecting mechanisms being all controlled in their operation by means of a single coin controlled mechanism which is common to them all.

A further object is to provide in a machine of this character improved means whereby when one of the ejecting mechanisms is being actuated, all of the other vending or ejecting mechanisms will be locked against operation, thereby rendering it impossible to actuate more than one ejecting mechanism at the same time.

A further object is to provide an improved machine of this character which will be comparatively simple and compact in construction, and effective and efficient in operation.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

30 Figure 1 is a front elevation of a machine of this character constructed in accordance with the principles of this invention.

Figure 2 is a vertical, sectional view taken on line 2—2, Figure 1, with parts omitted.

35 Figure 3 is a detail, horizontal, sectional view taken on line 3—3, Figure 2, on an enlarged scale, and with parts omitted.

Figure 4 is a vertical, sectional view on an enlarged scale, taken on line 4—4, Figure 2.

40 Figure 5 is a vertical, sectional view taken on line 5—5, Figure 2, on an enlarged scale.

Figure 6 is a detail, horizontal, sectional view taken on line 6—6, Figure 5, looking in the direction of the arrows and with parts omitted.

45 Figure 7 is a detail, vertical, sectional view taken on line 7—7, Figure 1, on an enlarged scale.

Figure 8 is a detail, sectional view, with parts omitted and parts broken away, as taken on line 8—8, Figure 7.

50 Figure 9 is a detail view partly in elevation, partly in section, and with parts omitted of a portion of the locking mechanism for the ejectors.

Figures 10 and 11 are elevations of details of 55 the locking mechanism.

Figure 12 is a detail, perspective view, of one of the ejecting mechanisms and a portion of the locking mechanism therefor.

Figure 13 is a view similar to Figure 7, with a portion of the mechanism omitted and showing 5 the parts in different positions from that shown in Figure 7.

Figure 14 is a view similar to Figure 8, showing the parts in another position.

Figure 15 is a detail sectional view showing the 10 manner in which the weight in the commodity holder will lock the ejector when the supply of articles is exhausted.

Figure 16 is a bottom plan view of the commodity feeding weight.

The machine consists essentially of a casing having an upper portion 15 and an enlarged base 16 of any desired size and configuration and constructed of any suitable material, the base being provided with an incline or chute, a portion 17 of 20 which is supported by the bottom of the casing to direct the articles to be vended through a delivery opening 18. Another portion 19 of the chute is secured to the back 20 of the casing, the latter being removably fastened in position by 25 means of a suitable lock 21.

Within the upper portion 15 of the casing is arranged a series of supply holders 22, the fronts of which are formed by a transparent closure 23, such as glass. The numeral 24 represents a back 30 for all of the supply holders and the back is removably secured in position by means of a member 25 behind which a portion of the back is inserted, and a pivoted catch 26 which cooperates with a keeper 27 so that when the back 35 20 is removed from the casing and the back 24 removed from behind the supply holders 22, the articles 28 may be placed in the supply holders in superposed positions.

Arranged within each of the supply holders 22 40 is a weight or follower 29 having a cut away portion 30 on the bottom thereof, for a purpose to be set forth, and the weight or follower rests upon the supplies 28 so as to cause the latter to be held in proper position to be engaged by the ejector. 45

As the construction and operation of each of the ejecting mechanisms for the respective supply holders is the same, the specific description of one will apply equally as well to them all.

Arranged within the base of the machine and 50 held in position in any suitable manner such as by means of brackets 31 (see particularly Figures 2, 4 and 5) is a support 32 which extends across the casing below the bottom of the supply holders and is held in position in any suit- 55

able manner, preferably by means of the brackets 31 being removably secured by means of fastening devices 33 to the side walls of the casing 15, so that when desired the support 32 together with 5 the associated mechanism may be readily removed from the back of the casing when the closure 20 is removed and the fastening devices 33 detached.

Mounted upon the support 32 are guideways 10 34 between which an upright 35 slides (see also Figure 3) and to the upper face of this upright is secured an ejector 36, the ejector being preferably held in position by means of two substantially U shaped members 37, the bottoms of 15 the U shaped portions abutting the upright member 35 and being held in position in any suitable manner, while the ejector 36 is secured to the upper flanges 38 of the U shaped members. The lower flanges 39 of the U shaped members pass 20 beneath the guides 34 and between the guides 34 and the support 32. The ejector 36 operates between flanges 40 formed at the bottom of the supply holders 22, and the commodity 28, when the ejector 36 is moved forwardly to allow the 25 commodities to drop, will rest upon the flanges 40 to be supported thereby, and the lowermost article in the supply will be in the path of the return movement of the ejector 36 to be ejected by such movement of the ejector and discharged 30 from the supply holder to drop upon the incline or chute 19-17 to be delivered through the delivery opening 18.

The upright member 35 constitutes a slide which projects through a suitable slot in the 35 front wall of the base 16 of the casing, and secured to the slide is an operating handle 41.

Provided on the edge of one of the flanges 39 (see particularly Figures 3 and 7) are a series of teeth 42 with which a spring controlled pawl 43 40 co-operates, a portion of the edge of the flange adjacent one end of the teeth being cut away as at 43^a, and another portion of the flange at the other end of the teeth being cut away as at 44, and these cut away portions 43^a and 44 are so 45 located with respect to the flange 39 and the movement of the slide 35 as to require the slide to move for a predetermined extent before the spring pressed pawl 43 passes out of engagement with the teeth 42 to permit the slide to be moved in the opposite direction. That is, the spring 50 pressed pawl or dog 43 co-operating with the teeth 42 on the slide operate as limit movement means necessitating the movement of the slide for a predetermined distance in each direction 55 before its direction of movement can be reversed.

A spring 45 is anchored by one end as at 46 to a stationary part of the mechanism and at its other end as at 47 to the slide 35 and tends 60 normally to retract the slide so as to move the ejector 36 into a position that it will be beneath the supply 28 (see Figure 7) to hold the supply in position.

It will thus be seen from the mechanism which has thus far been described, that when the slide 65 35 and ejector 36 are in their normal position, which is the position shown in Figure 7, the articles 28 will be supported by the ejector 36, but when the slide 35 is moved forwardly the ejector will be moved out from under the supply 70 and the supply will drop down and be supported by the flanges 40 on the walls of the commodity holder 22.

Pivotedly connected to the slide 35, preferably to one side thereof, is a dog 48 (see particularly 75 Figure 7) one end 49 of which projects for a sub-

stantial distance above the top of the slide 35, and the other end 50 of the dog is weighted so as to rest upon one of the flanges 39 of the U shaped members 37 that are connected with the slide 35 to form a stop for and to limit the movement of the dog 48 about its pivot in one direction. 5

The slides 35 are locked under certain conditions (to be explained) in a retracted position and against forward movement by means of a 10 locking bar or member 51 (see particularly Figures 5, 6 and 7), which latter is mounted to slide upon the bottom of the support 32 and is held in position in any desired or suitable manner, preferably by means of screws 52 which pass 15 through slots 53 in the bar 51 and into the support 32. A spring 54 is anchored by one end as at 55 to a fixed part of the machine and at its other end as at 56 to a projection depending from the slide 51 and tends normally to move the 20 slide in one direction, that is, in a direction to lock the slides. The slide is provided with upwardly projecting fingers 57 (see particularly 25 Figure 7) which project through a slot 58 in the support 32, so as to enter a recess 59 in the bottom of the slide 35 when the latter is in position to receive the fingers 57. This will occur when the parts are in the position shown in Figure 7, when the slide 35 has been retracted to the full extent of its rearward movement. 30

The bar 51, however, is not rendered active with respect to its locking position until a coin has been deposited into the machine, and then when the coin mechanism is subsequently actuated, the locking bar will become active in a 35 manner to be described.

Connected to the bar 51 is a depending member 60 arranged in any desired or suitable position which is adapted to be engaged and shifted by a suitable mechanism to be described, so as to move the bar 51 to the position shown in Figures 5 and 6, and against the stress of the spring 54 so as to unlock all of the slides 35 by moving the fingers 57 out of the respective recesses 59. This will permit any of the slides 35 to be selectively moved forwardly, and the member 60 and the bar 51 will be maintained in this position until other mechanism to be described, is operated, after which the member 60 will be released and the spring 54 will move the slide 51 back to a position to lock all of the slides 35, as will be described. 45

That is to say, normally the slides 35 are locked against movement by locking mechanism embodying the discs or elements 62 and 63, to be 55 hereinafter described, and the locking bar 51 is in a position that it will be inactive with respect to the locking of the slides 35, and will be held in this position by a portion of the coin controlled mechanism until a coin is deposited into the 60 mechanism and the handle 100 (to be described) is turned.

Normally, the projection 104 is in engagement with the depending portion 60 of the bar 51 and holds the bar back in an inactive position against the stress of the spring 54. 65

As soon as a coin is deposited into the opening 99, the handle 100 can be turned, and then the projection 104 will be moved out of engagement with the portion 60 and to such a position that 70 the spring 54 will move the bar 51 to temporarily lock the slides 35. The object of thus locking the slides 35 by the bar 51 at this point in the operation of the machine is to prevent the slides 35 from being moved until the coin is deposited into 75

- the machine. The parts will remain in this locked position until the handle 100 is released and returned to its normal position by the spring 105. Under the influence of this spring 105, the projection 104 will be moved back against the portion 60 of the bar 51 to shift the latter against the stress of the spring 54, to move the bar 51 into an unlocking position, the slides 35 will then be locked by the element 62—63.
- 10 In other words, the bar 51 serves only as a temporary locking means for the slides 35 during a portion of the operation of the machine and when the elements 62 and 63 are not serving as a locking means.
- 15 That is, the elements 62 and 63 co-operate with the bar 51 and vice versa, in controlling the operation of the device, and when one locking means is inactive the other is active.
- These two locking means permit a partial operation of the parts of the mechanism and thereby render the mechanism fraud-proof.
- Each of the slides 35 is provided with a downwardly projecting portion 61, see particularly Figures 7 and 8, which co-operates with two series 25 of freely movable members 62—63, each preferably consisting of a plurality of discs, the respective series being disposed to move in suitable spaced parallel guideways 65, which extend across and below each of the slides 35, the ends of the 30 guideways being closed by members 65^a adjustably held in position by screws 65^b. The guideways 64 and 65 are of such length with respect to the combined length of the diameters of the respective elements 62—63 that these elements may 35 be displaced laterally with respect to each other only for a sufficient distance to permit the downwardly extending portion 61 of one of the slides to pass therebetween, as shown more clearly in Figure 8. When one of these portions 61 is disposed between adjacent discs of each of the series 40 62 and 63, as shown in Figure 8, it will be impossible for any of the slides 35, except the one whose portion stands between the discs, to be moved forwardly, and this will lock all of the other slides 45 against movement. Such a movement of one of the slides 35 can only occur when the slides 35 have been released or unlocked by the shifting of the member 60 to withdraw the fingers 57 from the notches or recesses 59 in the slides.
- 50 By the provision of two sets or series of discs 62 and 63 and by the provision of other mechanism to be hereinafter described, which also operates to shift the discs 62 and 63, it will prevent one of the slides from being advanced until the 55 portion 61 of the slide which has been advanced has disengaged or passed out from between both series of discs 62 and 63. That is to say, it will prevent an operator from simultaneously operating two of the slides 35 at the same time.
- 60 In Figure 9, there is shown a locking mechanism which moves the discs 62—63 into such position within their guideways 64—65 so as to lock these discs against separation and prevent the advancement of any of the slides 35 until the proper 65 check or token has been deposited in the machine, in a manner to be set forth. This locking mechanism must first be released with respect to the discs or elements 62 so as to allow the discs to be separated to permit the portion 61 of one of the slides to pass between adjacent discs. After 70 the slide has been actuated and the commodity vended thereby, the locking mechanism is automatically actuated, according to the position of the slide so as to successively lock the series of 75 discs against separation as the portion 61 of one
- of the slides 35 passes from between adjacent discs.
- To that end there is provided a member 66 which is secured to a fixed support, preferably upon one of the guides 34 for the slides 35, and this member is preferably provided with a recess 67 in the upper edge thereof. A member 68 is connected to the member 66 for sliding movement with respect thereto, preferably by means of pins or bolts 69 which pass through the member 68 and through slots 70 in the member 66. The member 68 is provided on its upper edge with an upwardly inclined cam shaped portion 71 terminating adjacent a recess 72 opening through the top of the member, and the member 68 is held close to the side of the member 66 and is slideable with respect thereto. Depending from the member 68 is a projection 73 which extends through the support 32 and is adapted to pass between the wall 65^a at the end of the guideway 20 65 and the adjacent disc 63 so as to lock the disc 63 against separation.
- Sildably supported also by the member 66 and on the other side of the member 68 so that the member 68 will be therebetween is another slideable member 74 provided with slots 75 registering with and corresponding to the slots 70 in the member 66, so that the pins or bolts 69 supported by the member 68 will pass through the slots 75 as well as the slots 70, thereby adapting the members 68 and 74 for sliding movement with respect to the member 66 and also for independent sliding movement with respect to each other. Depending from the member 74 is a projection 76 which co-operates with the series of discs 62 in 30 the same manner that the projection 73 co-operates with the series of discs 63. That is, at a certain time in the cycle of operation of the machine, the projection 76 will pass between the wall 65^a at the end of the guideway 64 and the adjacent 40 disc 62 to lock these discs against separation and thereby prevent the drawing of any of the slides 35 forwardly, by reason of the fact that the discs being locked against separation, the portions 61 of the slides 35 cannot separate the discs and the 45 end of the portion 61 will abut the discs, and the slide will be held against forward movement.
- A spring 77 is anchored by one end to a fixed support 78 and by its other end to a pin 79 which is carried by the member 68 and projects through 50 one of the slots 70 in the member 66. Another spring 80 is anchored by one end as at 81 to a fixed support and by its other end to a pin 82 which is carried by the member 74, and is provided for the purpose of moving the member 74 55 with respect to the member 68 while the spring 77 is provided for the purpose of moving the members 68 and 74 with respect to the member 66.
- Depending from the member 68 is a pin or lug 60 83 which passes through a suitable slot 84 in the support 32 (see also Figure 6). A bell crank lever 85 is pivotally mounted as at 86 to the bottom of the support 32. One arm of this lever is bifurcated as at 87 and receives the pin 83 65 carried by the member 68. Connected to the other arm of the bell crank lever is a link 88, the link in turn being connected as at 89 to a lever or rocking member 90 pivotally supported 70 intermediate its ends as at 91 upon a suitable fulcrum 92, and the other end of the member 90 is provided with an enlarged or flattened portion 93 which is disposed adjacent but spaced from the member 60, which latter is connected 75

to the slide 51, for a purpose to be hereinafter described.

When this member 90 is rocked about its pivot in one direction, the bell crank lever 85 will be 5 rocked about its pivot and as the bell crank lever is connected to the slidable member 68 (see Figures 9 and 10) through the medium of the pin 83 and bifurcation 87 in the arm of the bell crank lever, the member 68 will be moved forwardly against the stress of the spring 77 until a bail 94, the arms 95 of which are journaled in bearings 96, passes over the cam shaped portion 71 on the member 68 to drop behind the cam shaped portion 71 into the recess 67 of the member 66, and thereby lock the member 68 in its forward position against the stress of the spring 77. A spring 97 may be provided for assisting the bail 94 in dropping from the cam 71 into the recess 67.

20 The spring 80 tends normally to move the member 74 with respect to the member 68 in a direction that the forward ends of the slots 75 in the member 74 (see particularly Figure 11) will abut the pins 69, with the result that when the member 68 is moved forwardly by the operation of the lever 90 and the intermediate connections, the pins 69 being carried by the member 68, the member 74 will also be moved forwardly and will be held in this position until the member 68 is released by the shifting or rocking of the bail 94 to move the latter from behind the cam shaped portion 71 on the member 68.

This operation will be effected by the dog 48 carried by the slide 35.

35 The normal position of the projection 76 on the member 74 is adjacent the endmost disc or element of the series 62 so as to lock them against separation, and the normal position of the projection 73 on the member 68 is adjacent the endmost disc or element of the series 63 to lock them against separation, so that the ends of the slides 35 cannot be moved forwardly until these projections 76 and 73 are displaced and moved to the position shown in Figure 8 to permit separation of the elements 62 and 63 of the 40 respective series, thereby permitting the projection 61 on the slide to pass between adjacent discs or elements to move the slide forwardly.

The normal position of the slides 35 (see particularly Figures 3 and 7) is such that the dog 50 48 will be disposed in the rear of the bail 94 when the latter is in a locking position, as shown in Figure 3, to lock the members 68 and 74 in their forward position against the stress of the respective springs 77 and 80, by reason of the fact that the bail will be behind the cam portion 71 on the member 68, resting in the recess 67 in the member 62, and as the pins 69 engage the forward end of the slot 75, the member 74 will also be held in its forward position.

60 This will cause the depending projection 73 on the member 68 and the depending projection 76 on the member 74 to stand in the positions with respect to the series of discs or elements 63 and 62, as shown in Figure 8.

65 Then when the slide 35 is moved forwardly by the operating handle 41, the end 49 of the dog 48 will contact the bail 94, and a further forward movement of the slide 35 in the same direction will rock the dog 48 from the full line position shown in Figure 7 to the dotted line position in said figure, thereby permitting the dog 48 to pass beneath the bail 94 and the depending portion 61 of the slide 35 to pass between respective adjacent discs 62 and 63, per-

mitting a full forward movement of the slide 35.

As soon, however, as the end 49 passes the bail 94, the weighted end 50 will cause the dog to move back into the full line position shown in Figure 7, but in advance of the bail 94.

When the slide 35 is then moved rearwardly back to its normal position, and during which time the article 28 will be ejected from the supply 22 by the ejector 36, the dog 48 will be in a somewhat rigid position with respect to the slide 10 35, with the result that as the slide 35 moves rearwardly the end 49 of the dog will engage the bail 94 and raise the bail against the stress of the spring 97, thereby releasing the members 68 and 74, but as the discs or elements of the respective series 62 and 63 are projected into the path of the rearward movement of the projections 73 on the members 68 and 76 on the member 74, these members will be held against rearward movement, but the respective springs 27 and 80 15 will be maintained under tension so that when the discs or elements 62—63 are respectively moved out of the path of the movement of the projections 73 and 76, in a manner to be set forth, the members 68 and 74 will then be allowed to 20 return under the stress of the springs 77 and 80.

When the members 68 and 74 are in their forward positions (see particularly Figure 8), the projection 76 on the member 74 will be disposed to one side of the guideway 64 of the series of 30 elements 62 while the depending projection 76 on the member 68 will be disposed between the series of elements 62—63, allowing both series of elements 62—63 to be separated at any predetermined point by the depending portion 61 on the 35 selected slide 35, so as to permit that slide to be moved forwardly to eject a predetermined one of the supplies 22 from which the article is to be vended upon the return stroke of the slide, while the other slides 35 will be locked against forward 40 movement by the elements 62.

In Figure 8 the position of the projections 76 and 73 is clearly shown when the elements 62 and 63 have been separated by the depending portion 61 of one of the slides 35, and it will be manifest 45 that in this position of the elements 62, all of the remaining slides 35 will be locked against being moved forwardly.

This is the position the parts will assume when the slide 35 is drawn forwardly and the dog 48 50 is being rocked by engagement with the bail 94 to pass the latter in a forward direction.

When, however, the slide 35 is at the limit of its forward movement and the dog 48 has dropped back to the position shown in full lines in Figure 55 7, and the slide 35 is being returned so as to eject the article, the dog 48 will raise the bail 94 to release the member 68 and also the member 74. The spring 77 being under tension will immediately have the tendency to move the members 68 60 and 74 backwardly, but as the depending portion 61 of the slide 35 stands between adjacent discs or elements of the series 62—63, one of the discs of the forward series 63 will stand within the path of the return movement of the projection 65 73 on the member 68 and hold it against return movement under the stress of the spring 77. At the same time one of the discs or elements of the series 62 will stand within the path of the return movement of the projection 76 on the 70 member 74, holding that member against return movement under the stress of the spring 80.

The parts will remain in this position until the depending portion 61 on the slide 35 clears the discs or elements of the forward series 63. At 75

this moment the stress of the spring 77 being exerted upon the member or slide 68 will move the projection against the end disc or element 63 to shift the latter and allow the projection 73 to pass, thereby permitting the spring 77 to move the member 68 to its rearmost position, and lock all of the discs or elements 63 against separation. At the same time, however, the member 74 will be prevented from a similar movement under 10 the stress of the spring 80 by reason of the fact that one of the discs of the series 62 will be in the path of the return movement of the projection 76 on the member 74, due to the fact that the portion 61 of the slide 35 has not yet 15 been removed from between the discs of the series 62.

The parts will remain in this position until the portion 61 of the slide 35 clears or passes from between the discs or elements 62 of the rear- 20 most series and just as the said portion 61 does clear the elements 62, the spring 80 will cause the depending portion or projection 76 on the member 74 to pass into such a position with respect to the disc 62 to lock them against separation. 25

This double series of elements 62—63 prevents the manipulation of the machine so as to partially advance one of the slides before the other 30 slide is completely returned and the elements 30 62—63 will be locked against separation, so as to further prevent the delivery of an article from the machine without the deposit of the proper coin or check.

It will be manifest that the two series of discs 35 will be successively locked against separation, and this will insure the operation of only one of the slides 35, while the others remain locked against operation.

The ejecting mechanism is controlled in its 40 operation by a coin controlled device designated generally by the reference numeral 98 having a coin receiving inlet 99 and an operating handle 100. This coin controlled mechanism may be of any suitable type. Suffice it to say that there is 45 provided a rotatable element 101 preferably embodying a shaft 102 having a cut away portion 103 and carried by the portion 103 is a projection 104. This shaft is disposed between the member 60 and the lever 90, as shown more clearly in 50 Figure 4, and connected to the shaft is a spring 105, one end of which is anchored as at 106 to the shaft and the other end at 107 to a fixed support.

The normal tendency of the spring 105 is to 55 return the shaft to its normal position, that is to the position shown in Figures 4 and 5, so that upon insertion of a coin into the coin receiving opening 99 and the rotation of the operating handle 100, the shaft 101 will be first rotated in 60 the direction indicated by the arrow in Figure 4, to cause the projection 104 to engage the end 93 of the lever 90 and rock the latter about its pivot 91 to draw the members 68 and 74 forwardly so that the bail 94 will drop behind the 65 cam portion 71 on the member 68 and into the recess 67 on the member 66, thereby moving these members forwardly so as to move the projections 73 and 76 to the positions shown in Figure 8, to release the discs or elements 63 and 62 70 so that they may be separated by one of the slides 35 being moved forwardly. Upon this movement of the shaft 101, the projection 104 will move out of engagement with the member 60 to allow the spring 54 to shift the member 51, 75 to cause the projections 57 to enter the recesses

59 in the slides 35 to temporarily lock them against movement.

After the members 68 and 74 have been thus locked in their forward position and in the position shown in Figure 8, by the rotation of the operating handle 100, the spring 105 is being placed under tension so that when the handle 100 is released, the shaft 101 will be rotated in the opposite direction, causing the projection 104 to engage the member 60 which is connected to the slide 51 to move the latter (see Figure 7) and cause the fingers 57 to move out of the notch or recess 59 in each of the slides, so that one of the slides 35 may be selected to be advanced and then retracted to deliver an article from the respective supply. 15

During this operation of the shaft 101 the coin or token will be discharged through the opening 98 into the coin receiving receptacle 109 within 20 the base of the machine.

It is thought that the operation of this device will be clearly understood from the foregoing, but briefly stated it is as follows:

The normal position of the slides 35 is as shown in Figure 7 with the ejector 36 of the respective 25 slides disposed beneath the supply 28 and with the projections 76 and 73 on the respective members 74 and 68 in such position with respect to the elements 62—63 (see Figure 14) as to lock them against separation, and in which position 30 the members 68 and 74 will be held retracted by the respective springs 77—80.

When a coin is deposited in the coin receiving opening 99, and the handle 100 rotated, the coin, through the coin controlled mechanism (not 35 shown) will connect the handle 100 with the shaft 101, so that the latter may be rotated against the stress of the spring 105. The first operation is that the projection 104 on the shaft 101 will engage the portion 93 of the lever 90 40 and rock it about its pivot, thereby rocking the bell crank lever 85 (see Figure 6) which will cause the members 68 and 74 to be moved forwardly to a position that the bail 94 will drop behind the cam 71 on the member 68 and into 45 the recess 67 in the member 66, the member 74 being moved and held forwardly by means of the pins 69 engaging the forward ends of the slots 75.

The handle 100 is then released and the spring 50 105 will return it to its normal position, during which time the projection 104 will move into engagement with the member 60 on the slide 51 and unlock the slides 35 by moving the fingers 57 thereof out of the notches or recesses 59. 55

The discs 62 and 63 being thus unlocked by reason of the fact that the projection 76 on the member 74 and the projection 73 on the member 68 will move into positions out of engagement with the discs or to such positions as to permit 60 the discs 62—63 to be separated, the machine will be unlocked.

The operator then can select any one of the slides 35 and draw the same forwardly. By reason of the fact that the discs 62 and 63 are unlocked, they will be separated by the portion 61 of the slide 35 to permit the latter to be moved forwardly. This movement, however, of the portion 61 with respect to the elements 62 and 63 will lock the latter against being separated so as 70 to permit any one of the slides 35 to be moved forwardly, and lock the other slides against forward movement, when one slide has already been moved forwardly.

As the slide 35 moves forwardly, the dog 48 75

will be rocked about its pivot to pass under the bail 94 and the full extent movement pawls 43 passing over the ratchet teeth 42 will necessitate the movement of the slide forwardly to its 5 full extent before the pawl can pass into the recess 43^a to permit the pawl to reverse and thereby render it possible to return the slide 35 to eject the article from the supply.

As the slide 35 returns, the dog 48 will engage 10 the bail 94 and shift the latter to move it from behind the cam 71 of the member 68. This will release both the members 68 and 74, so that they will be subject to the stress of their respective springs 77 and 80 but, inasmuch as the projections 15 73 and 76, (see Figure 8) on these members 68 and 74 will be held against return movement by the discs 63 and 62, by reason of the portion 61 of one of the slides 35 being between the discs, these members 68 and 74 will be held against return movement.

When the portion 61 of the slide 35 has moved 20 out of engagement or from between the discs of the series 63, the spring 77 which controls the movement of the slide or member 68 to which the projection 73 is connected, will move the member 68 rearwardly and the projection 73 into such position with respect to the series of elements 63 as to lock them against separation. However, as the portion 61 of the slide 35 is still 25 between the discs 62, the member 74 will be held against return movement under the stress of its spring 80 until the portion 61 of the slide moves from between the discs 62 so as to allow the spring 80 to act upon the member 74, drawing 30 the projection 76 backwardly against the adjacent element 62, causing the elements to be shifted in such a manner that they will be locked against separation.

Until a new coin has been inserted in the machine and this operation repeated, it will not be possible to operate another slide, and it will be impossible to operate one slide when another slide has been partially or fully operated.

As soon as the supply of articles has been exhausted 40 from any one of the supply holders 22, the weight 29 will drop downwardly so that the cut away portion 30 thereon will assume a position in the path of the forward movement of the ejector 36 so as to be engaged by the ejector, 45 and this will hold the slide 35 of the exhausted supply from being moved forwardly.

In order to lock the ejector slide against operation when the respective supply is exhausted, the weight 29 drops down, so that a shoulder 29^a 50 on the bottom thereof, will move into the path of movement of the edge 36^a of the portion 36 of the ejector, as shown in detail in Figure 15 of the drawings.

While the preferred form of the invention has 60 been herein shown and described, it is to be understood that various changes may be made in the details of construction and in the combination and arrangement of the several parts, within the scope of the claims, without departing 65 from the spirit of this invention.

What is claimed as new is:—

1. In a vending machine, a plurality of article supply holders, ejecting mechanisms individual to the supplies, means for locking said ejecting 70 mechanisms against operation, a normally inactive master control, means whereby said master control may be rendered active to render said locking means inactive to permit said ejecting mechanisms to be selectively rendered active to 75 eject an article from its respective said supply,

means responsive to the operation of the ejecting mechanisms for locking the remaining ejecting mechanisms against operation, additional means common to the ejectors for locking them against operation, and mechanism embodying a 5 portion of the first said means, operable to render the last recited locking means inactive.

2. In a vending machine, a plurality of ejectors, means normally locking said ejectors against operation, said means embodying a plurality of 10 freely movable members adapted to be separated to permit only one of the ejectors to be actuated while said members operate to lock the other ejectors against operation, means individual to the ejectors for separating the said members, for 15 selectively rendering an ejector active, means tending normally to lock said members against separation, means for maintaining the last said means in inoperative position, and means individual to and connected to the ejectors, movable 20 therewith and with respect thereto for rendering the last said means inactive, thereby adapting the said locking means to return to their active or locking positions.

3. In a vending machine, a plurality of ejectors, means normally locking said ejectors against operation, said means embodying a plurality of 25 freely movable members adapted to be separated to permit only one of the ejectors to be actuated while said members operate to lock the other ejectors against operation, means individual to the ejectors for separating the said members, for selectively rendering an ejector active, means adapted to be positioned to lock 30 said members against separation, means for positioning the last recited locking means in an inactive position, to permit the said members to be separated, means for maintaining the locking means in an inactive position, and means individual to the ejectors operating to render the 35 last recited locking means active at a predetermined time in the cycle of operation of the ejector.

4. In a vending machine, a plurality of ejectors, means normally locking said ejectors against 45 operation, said means embodying a plurality of freely movable members adapted to be separated to permit only one of the ejectors to be actuated while said members operate to lock the other ejectors against operation, means individual 50 to the ejectors for separating the said members, for selectively rendering an ejector active, an element, means tending normally to position said element for locking said members against separation, means for positioning said element to 55 render the same inactive to permit the said members to be separated, means for locking said element in its last said position, and means individual to and responsive in its operation to the 60 operation of the ejectors for rendering the said locking means active.

5. In a vending machine, a plurality of article supply holders, ejectors individual to the supplies, means individual to said ejectors for actuating them, means common to the ejectors for locking them against operation, check controlled mechanism common to said ejectors for rendering the said locking means inactive, additional means normally locking said ejectors against operation, 70 means adapted to be set by the operation of the check controlled mechanism, to render the said additional means inactive with respect to locking the ejectors against operation, and means responsive to and operating at a predetermined 75

time in the cycle of operation of the ejectors for causing the said additional means to lock all of the ejectors against operation.

6. In a vending machine, a plurality of article supply holders, ejectors individual to the supplies, means individual to said ejectors for actuating them, means common to the ejectors for locking them against operation, check controlled mechanism common to said ejectors for rendering the said locking means inactive, additional means for locking said ejectors against operation, normally active means for rendering the last said means active, means whereby upon operation of the check controlled mechanism the last recited means will be rendered inactive, means for locking the latter in an inactive position, and means individual to the ejectors and operating upon the actuation of any ejector to release the last said locking means to permit the said normally active means to return to their locking positions.

7. In a vending machine, a plurality of slideable ejectors, means for locking the ejectors against operation, said means embodying a plurality of freely separable elements arranged in alignment and adapted to be separated to permit one of said ejectors to be actuated, means for maintaining said elements against separation to maintain all of the ejectors against operation, a master control, means responsive in its operation to the actuation of said master control for rendering the last recited means inactive whereby said members may be separated by the operation of one of the ejectors, and maintained against separation with respect to the remaining ejectors to lock the latter against operation, and means separate from said master control and itself controlled in its operation by the actuation of one of the ejectors for rendering active the means which prevents the said elements from being separated.

8. In a vending machine, a plurality of slideable ejectors, means for locking the ejectors against operation, said means embodying a plurality of series of freely separable elements, the elements of each series adapted to be selectively separated to permit one of said ejectors to be actuated, means individual to the series for maintaining the elements of the respective series against separation, means adapted to render the last recited means inactive to permit the elements to be separated with respect to one of the ejectors and against separation with respect to the remaining ejectors to lock the latter against operation, and means responsive in its operation to the actuation of any of the ejectors for successively rendering the second recited means active, to restore, at predetermined times in the cycle of operation of the ejector, the normal position of the said elements with respect to each other and for locking the elements against separation.

9. In a vending machine, a plurality of slideable ejectors independently operable, means for locking the ejectors against operation, said means embodying a series of freely separable elements arranged edge to edge, means carried by the ejectors for separating said elements to permit an ejector to be actuated, the first said means embodying means for maintaining the elements against separation, means for rendering the last said means inactive, locking means adapted to be rendered active to maintain the last said means in an inactive position whereby said ele-

ments may be separated with respect to one of said ejectors only, and means operable in response to the actuation of an ejector to render the second recited locking means inactive, whereby the third recited means will become active to maintain the said elements against separation. 5

10. In a vending machine, a plurality of slideable ejectors independently operable, means for locking the ejectors against operation, said means embodying a series of freely separable elements arranged edge to edge, means carried by the ejectors for separating said elements to permit the ejector to be actuated, means for maintaining the elements against separation, means tending normally to maintain the last said means active, mechanism adapted to be set to maintain the said separation preventing means inactive against the stress of the fourth said means, whereby said elements may be separated with respect to one of said ejectors only, and means responsive in its operation at a predetermined time in the cycle of operation of the operable ejector for rendering the said mechanism inactive, whereby the third recited means will become active to maintain the said elements against separation. 10 15 20 25

11. In a vending machine, a plurality of slideable ejectors independently operable, means for locking the ejectors against operation, said means embodying a series of freely separable elements arranged edge to edge, means carried by the ejectors for separating said elements to permit the ejector to be actuated, the first recited means embodying means for maintaining the elements against separation, mechanism adapted to be set to maintain the last said means inactive whereby 30 35 40 45 said elements may be separated with respect to one of said ejectors only, means responsive to the operation of the actuatable ejector operating to render the said mechanism inactive whereby the third recited means will become active to maintain the said elements against separation, coin controlled mechanism, and means responsive in its operation to the actuation of the control mechanism for setting the first recited mechanism.

12. In a vending machine, a plurality of slideable ejectors independently operable, means for locking the ejectors against operation, said means embodying a plurality of separate series of freely separable elements, the elements of each series being arranged edge to edge, and the series being spaced from each other, means carried by the ejectors for successively separating the elements of the two series to permit the ejector to be actuated, means individual to the series for maintaining the elements of the respective series against separation, a control device mechanism individual to the said series adapted to be set in response to the operation of said control device, to maintain the last said means inactive 50 55 60 65 whereby said elements of the respective series may be separated with respect to one of said ejectors only, and means operating in response to the operation of said ejectors to successively render said mechanisms inactive whereby the third recited means will become active to maintain the elements of the respective series against separation.

13. In a vending machine, a plurality of slideable ejectors independently operable, means for locking the ejectors against operation, said means embodying a plurality of separate series of freely separable elements, the elements of each series being arranged edge to edge, means carried by the ejectors for successively separating the elements 70 75

of the two series to permit the ejector to be actuated, means individual to the series for maintaining the elements of the respective series against separation, mechanism individual to the said series adapted to be set to maintain the last said means inactive whereby said elements of the respective series may be separated with respect to one of said ejectors only, coin controlled mechanism for controlling the operation of the said mechanism that is adapted to be set, and means responsive in its operation to the actuation of the ejector at a predetermined point in its cycle of operation to successively render said mechanisms inactive whereby the third recited means will become active to maintain the elements of the respective series against separation.

14. In a vending machine a plurality of separately slideable ejectors, means for locking the ejectors against operation, said means embodying a plurality of series of freely separable members, means individual to the series for maintaining the members therein against separation, the last said means embodying shiftable elements adapted to be positioned with relation to the respective series, coin controlled means for moving said elements out of the last recited positions, locking means for maintaining them in the positions into which they have been moved, to permit the said members to be separated with respect to one ejector only, and means for rendering said locking means inactive to permit said elements to be successively moved into positions to prevent separation of said members.

15. In a vending machine a plurality of separately slideable ejectors, means for locking the ejectors against operation, said means embodying a plurality of series of freely separable members, means individual to the series for maintaining the members therein against separation, the last said means embodying shiftable elements adapted to be positioned with relation to the respective series, coin controlled means for moving said elements out of the last recited positions, locking means for maintaining them in the positions into which they have been moved, to permit the said members to be separated with respect to one ejector only, and means controlled in its operation by the actuation of an ejector for causing the means which prevents the elements from being separated, to become active.

16. In a vending machine, a plurality of slideable ejectors, means for maintaining them against operation, said means embodying a plurality of series of elements arranged edge to edge and adapted to be selectively separated to permit the operation of one of the ejectors, means embodying slideable members individual to the series and adapted to be positioned with respect to the series to prevent separation of the elements, means connecting said members for movement together and for separate movement one with relation to the other, coin controlled means for positioning said members to permit the elements to be separated, means for locking the members in such position, means for rendering the said locking means inactive, and means tending normally to move the members when unlocked, into a position to prevent separation of the elements.

17. In a vending machine, a plurality of slideable ejectors, means for maintaining them against operation, said means embodying a plurality of series of elements arranged edge to edge and adapted to be selectively separated to permit the operation of one of the ejectors, means embodying

adapted to be positioned with respect to the series to prevent separation of the elements, means connecting said members for movement together and for separate movement one with relation to the other, coin controlled means for 5 positioning said members to permit the elements to be separated, means for locking the members in such position, means for rendering the said locking means inactive, means tending normally to move the members when unlocked, into a 10 position to prevent separation of the elements, the means which renders the said locking means inactive, embodying a pivoted locking element co-operating with a portion of one of said members, and an element carried by the ejector for 15 engaging and moving the said pivoted locking element.

18. In a vending machine, a plurality of slideable ejectors, means for maintaining them against operation, said means embodying a plurality of 20 series of elements arranged edge to edge and adapted to be selectively separated to permit the operation of one of the ejectors, means embodying slideable members individual to the series and adapted to be positioned with respect to the series 25 to prevent separation of the elements, means connecting said members for movement together and for separate movement one with relation to the other, coin controlled means for positioning said members to permit the elements to be separated, 30 means for locking the members in such position, means for rendering the said locking means inactive, means tending normally to move the members when unlocked, into a position to prevent separation of the elements, the means 35 which renders the said locking means inactive, embodying a pivoted locking element co-operating with a portion of one of said members, and an element carried by the ejector for engaging and moving the said pivoted locking element, 40 the said element which is carried by the ejector being pivoted thereto and adapted to engage said locking element and be moved about its pivot thereby to pass the locking element when the ejector is moved in one direction, and adapted 45 to engage and swing the locking element about its pivot when the ejector is moved in the opposite direction.

19. In a vending machine, a plurality of slideable ejectors, means individual thereto for operating them, means normally locking the ejectors against operation and embodying a plurality of freely movable members adapted to be separated to permit only one of the ejectors to be actuated while said members operate to lock the other 55 ejectors against operation, means individual to the ejectors for separating the said members, an element for locking the members against separation, means tending normally to render said element active, means for moving said element into 60 an inactive position, means for locking the element in an inactive position, the last said means embodying a member adapted to be tripped upon movement of the ejector in one direction, and means individual to and carried by the ejector 65 for tripping the last said member, the tripping means embodying a member movable with and with respect to the ejector.

20. In a vending machine, a plurality of slideable ejectors, means individual thereto for operating them, means normally locking the ejectors against operation and embodying a plurality of freely movable members adapted to be separated to permit only one of the ejectors to be actuated 70

ejectors against operation, means individual to the ejectors for separating the said members, an element for locking the members against separation, means tending normally to render said element active, means for moving said element into an inactive position, means for locking the element in an inactive position, the last said means embodying a member adapted to be tripped upon movement of the ejector in one direction, and 10 means individual to and carried by the ejector for tripping the last said member, the tripping

means embodying a member pivotally mounted upon the ejector, a stop to be engaged by the last said member to arrest its movement about its pivot when the tripping member contacts the locking member whereby the former will be 5 tripped by the latter, said tripping member freely movable about its pivot in the opposite direction when contacting the locking member, upon the movement of the ejector in the opposite direction.

ALBERT E. GEBERT. 10
FLOYD C. BLACK.
